UNITED STATES PATENT OFFICE.

ALBERTO BAGNULO, OF TURIN, ITALY.

INTERNAL-COMBUSTION AND HOT-AIR ENGINE.

1,423,705.

Specification of Letters Patent. Patented July 25, 1922.

Application filed September 23, 1919. Serial No. 325,670.

To all whom it may concern:

Be it known that I, ALBERTO BAGNULO, a subject of the King of Italy, residing at 13 Via Bogino, Turin, in the Kingdom of Italy, 5 have invented certain new and useful Improvements in Internal-Combustion and Hot-Air Engines; and I do hereby declare the following to be a full, clear, and exact description of the invention, such as will 10 enable others skilled in the art to which it appertains to make and use the same, reference being had to the accompanying drawings, and to letters or figures of reference marked thereon, which form a part of this 15 specification.

This invention relates to a four-stroke internal combustion engine, in which the working cylinder is provided with an auxiliary vaporizing and combustion chamber, to 20 which the fuel is delivered, characterized by the fact that the auxiliary chamber is constituted by a small vaporizer arranged parallel to and at one side of the cylinder and in constant communication therewith, and 25 is provided at its top with a fuel feeding device comprising a hand-controlled cock and an automatic stop valve, so that the fuel is admitted to the vaporizer during the exhaust and suction stroke, and may therefore 30 completely vaporize in a space without air, the air necessary for combustion being introduced into the vaporizer during the engine compression stroke.

This improved engine has a great efficiency, and is of a very simple and strong construction. The fuel striking against the highly heated surface of the vaporizer has sufficient time to fully vaporize, so that when 35 the air enters the vaporizer during compression, it is possible to obtain a thorough combustion. The working cylinder is not damaged by the high temperature of the combustion in the vaporizing chamber, as this latter is separated therefrom, while 40 there is drawn into the cylinder an excess of air that does not prevent complete combustion; therefore an energetic cooling of the working cylinder is not required.

In the annexed drawing is shown by way 45 of example a constructional form of the engine in vertical section forming the object of the invention.

The vaporizing and combustion chamber 1 is chiefly constituted by a small vessel 50 placed laterally of and parallel with the working cylinder 2, with the upper end of

which it is in constant communication by means of the passage 3. This passage 3 enlarges from the engine cylinder toward the vaporizing chamber 1. On its top 4 is 60 axially placed the liquid fuel supply means that comprises a needle or regulating rod 5 with conical end operated by a hand wheel 6 controlling the passage of the fuel into the chamber 1 through a pipe 7; an automatic ball valve 8 closes the pipe 9 admitting the fuel to the fuel supply means as soon as the pressure in the combustion chamber is higher than in the fuel tank. 65

In order to pulverize or atomize the fuel 70 when entering the vaporizer and throw it against the walls of this latter, a cone bunsen 10 is arranged under the pipe 7.

The fuel during the exhaust and suction strokes falls in small drops into the chamber 75 1, where, owing to the high temperature, (produced at starting by externally heating the chamber 1 by means of a suitable source and during working by the heat generated by the successive combustions) is vaporized 80 but will not burn owing to lack of air. During the compression stroke, the air, before being drawn through the cylinder by the piston, gradually enters the vaporizing chamber and is combined with the fuel 85 vapors that are developed therein during the exhaust and suction and at the beginning of the compression stroke, thus effecting a complete combustion.

The gases burnt in the vaporizing chamber will flow into the working cylinder 2, 90 heating the air left therein and effecting therewith the expansion stroke.

From the above it will be understood that the zone of the highest temperature is completely separated from the working cylinder, as the fuel vaporization and the formation and burning of the mixture are effected in the chamber 1. Therefore the engine is in the best working conditions, and moreover 100 it is possible to maintain constantly in the engine such a high temperature that a complete vaporization of the fuel will be assured.

I claim—

1. In a heavy oil, four stroke cycle, internal combustion engine, the combination with the engine cylinder; of a vaporizing and combustion chamber arranged laterally of the cylinder and in constant communication therewith, and a fuel feeding device 110 above the vaporizing chamber and dis-

105

110

charging vertically, said device comprising a fuel regulating valve and an automatic ball valve controlling the fuel supply to the regulating valve, arranged to feed fuel 5 to the vaporizer during the exhaust and suction strokes of the engine when the pressure within the engine cylinder becomes less than the fuel pressure.

2. In a heavy oil, four stroke cycle, internal combustion engine, the combination 10 with the engine cylinder; of a vaporizing and combustion chamber 1 arranged later-

ally of the cylinder and in constant communication with the cylinder by a passage 3 enlarging toward said chamber, a fuel feeding device above said chamber comprising a fuel regulating valve 5, an atomizing device below said valve and an automatic ball valve 8 between the regulating valve and fuel supply.

20

In testimony that I claim the foregoing as my invention, I have signed my name.

ALBERTO BAGNULO.
